M. L. Smith, Esq.

UNITED STATES PATENT OFFICE.

HUBERT F. JONAS, OF OSHKOSH, WISCONSIN, ASSIGNOR OF TWO-THIRDS TO
FRANK R. MARSHALL, GEORGE F. MARSHALL, AND MIKE F. MILLER, OF
SAME PLACE.

BAG-HANDLE.

SPECIFICATION forming part of Letters Patent No. 594,176, dated November 23, 1897.

Application filed January 20, 1897. Serial No. 619,991. (No model.)

To all whom it may concern:

Be it known that I, HUBERT F. JONAS, a citizen of the United States, residing at Oshkosh, in the county of Winnebago and State of Wisconsin, have invented certain new and useful Improvements in Bag-Handles; and I do declare the following to be a full, clear, and exact description of the invention, such as will enable others skilled in the art to which it applies to make and use the same, reference being had to the accompanying drawings, and to the letters of reference marked thereon, which form a part of this specification.

My invention relates to improvements in bag-handles.

In making the handles I preferably employ the following method: first, in providing a mold in which the filling material is compressed in the proper form between the enveloping pieces of leather and at the same time the top piece of leather is properly marked for stitching; second, in then stitching the top and bottom pieces of leather together, so as to properly envelop and secure the filling; 25 and also to provide an edge stitching to afterward be upturned; third, then trimming the edges to the proper shape in conformity with the outer stitching; fourth, in then reversing the sides and crimping the handle in another 30 mold to a proper and symmetrical shape, turning the outer edges upwardly and around the filling to partially inclose the same. The article when so completed presents a beautiful appearance, is symmetrical in shape, and 35 is without any seam or edge at the point of contact with the hand in carrying the bag.

In the accompanying drawings, Figure 1 is a plan view, and Fig. 2 is a vertical section, of the handle before crimping. Fig. 3 is an 40 end view of the top and bottom molds. Fig. 4 is a plan view, and Fig. 5 a side view, of the handle after being crimped. Fig. 6 is a cross-section of the handle after crimping.

Similar letters refer to similar parts in each 45 view.

A is the top piece of leather, and B the bottom piece of leather in the first construction of the article. Afterward, when crimped, these are transposed, A being at the bottom, 50 designed to come in contact with the hand and partially surrounding the strip B, as shown in Figs. 4 and 5.

C is the filling, which may be of any fibrous material capable of being properly compressed in the molds.

55

Fig. 3 represents the mold used to first compress the article into the proper shape, A' being the top portion of the mold, and B' being the bottom portion. The bottom piece of leather B, Fig. 2, is first arranged in the bottom of the mold B'. The filling C is then placed longitudinally in the bottom depression b. Then the top piece of leather is placed upon these as a covering enveloping the filling and the top portion of the mold A' 60 pressed downwardly. The longitudinal projections a' a' a' a' mark the proper locality upon the top portion of the upper strip for stitching. The two engaging surfaces of the upper and lower pieces of leather are pasted, 65 so as to properly adhere before stitching. After allowing the article to remain in the mold for a sufficient length of time to set it is removed and stitched by an ordinary sewing-machine along the outer edges D D, Fig. 1, 70 and at the inner seams D' D', next to the core or filling C. Then a pattern is placed upon the article and the outer edges, Fig. 1, trimmed closely to the seams D D to make the desired shape. The article is then 75 reversed, the upper covering A being below, and vice versa, and is then crimped to the shape shown in Fig. 5 by molds similar to those shown in Fig. 3. A series of molds can be used and several handles crimped at once. 80 The strip A is turned upwardly around the core in crimping, so as to partially envelop the same, thus exposing to view only the face side of the stitching and providing a smooth and unbroken surface to engage the hand in 85 carrying the bag.

My invention as an article of manufacture can be rapidly and cheaply made entirely by machinery, if so desired, has a beautiful and symmetrical shape and appearance, and is 90 easy to the hand in carrying.

In the construction of the better grade of handles the outer edges D D may be rolled edges, the edge of the strip A turned over the edge of the strip B and stitched, so as to 100 surround the same in the finished product. Eyelets may be inserted into the handle or other methods provided for the purpose of attaching it to the bag or satchel.

By means of my invention I am able to reduce the amount of leather used in the manufacture to a minimum, being much less than has been used in leather handles heretofore constructed and used.

Having described my invention, what I claim is—

1. As an improved article of manufacture a handle for bags or similar articles, consisting of upper and lower pieces of leather stitched together and each provided with two edges forming side extensions, a suitable filling between said pieces, the two joined edges of the pieces of leather on opposite sides being turned up around the central portion to form a smooth handhold, substantially as described.

2. As an improved article of manufacture a handle for bags or similar articles, formed of upper and lower pieces of leather, a suitable filling interposed between the said pieces, stitches arranged longitudinally and inclosing said filling, the opposite edges of each piece extending considerably beyond the stitching around the filling, and having their outer edges also stitched together, opposite joined edges being turned up upon either side of the central filled portion to present a smooth surface to the hand, substantially as described.

3. As an improved article of manufacture

a handle for bags or similar articles formed of upper and lower pieces of leather, a suitable filling interposed between said pieces, stitches arranged longitudinally of said pieces and inclosing said filling, the two opposite edges of said pieces extending considerably beyond the stitching and being turned up around the filling to form side coverings for inclosing the central filled portion whereby a smooth surface is presented to the hand and attaching-eyes secured in the ends of said handles for securing it to said bag or other article, substantially as described.

4. As an improved article of manufacture a handle for bags or similar articles consisting of upper and lower pieces of leather, a suitable filling interposed between said pieces and arranged longitudinally thereof, stitches passed through said pieces of leather so as to inclose said filling, the two edges of each piece extending some distance beyond the filled portion and both of said edges turned up around the same to present a smooth surface to the hand, substantially as described.

In testimony whereof I affix my signature in presence of two witnesses.

HUBERT F. JONAS.
